UNITED STATES PATENT OFFICE.

JOHN W. WOLSTENHOLME, OF NEWTON, NEW JERSEY.

TEXTILE-PRINTING MACHINE.

Application filed March 15, 1927. Serial No. 175,444.

The present invention relates to an improvement in textile printing machines. One object thereof has been to provide apparatus wherein a single part may effectively be used in a multiplicity of operations which have heretofore required a plurality of parts, and more particularly to do away with the present necessity of carrying as equipment a large number of copper gum water rollers of divers sizes corresponding to the sizes of printing rollers for a large number of different patterns or designs. A further object has been to improve the quality of textile printing machines by eliminating the structural defects therein which have heretofore been largely responsible for certain imperfections in printing.

In the operation of well known types of machines it has been customary to feed the web of fabric between a central drum or cylinder and one or more printing rolls co-operating therewith, said rolls being geared to rotate in synchronism with the cylinder. A gum water roller, bruiser, or crush roller is usually positioned to operate on the fabric after the last printing roller or rollers. Or, where the design involves the use of more than one printing roller, a gum water roller may advantageously be positioned to operate between printing rollers. In either case the gum water roller is geared to rotate in synchronism with the printing roller and the cylinder. Its function is to remove all surplus dye or color and to press the previously deposited dye or color into the fabric while applying a protective coating solution thereto. Where the printing rollers and the gum water roller or rollers are geared together and with the cylinder, each will be a portion of positively operating feeding mechanism for the web of fabric. It is therefore essential that their peripheral surfaces shall rotate at a uniform speed. Otherwise the section of fabric web between printing rollers or between a gum roller and a printing roller may become slack or unduly taut either of which conditions will cause a defect in the printing, such as blurring, or dragging of one color into another. In practice, the components of the printed pattern or design are incorporated in the peripheral surfaces of the printing rollers. After the desired output of any design has been completed, the peripheral surfaces of the rollers are cut or turned down to provide fresh sur-

faces for new designs. Obviously, where the gear ratios are fixed, the rollers must be of equal diameter. This means that the gum water roller must also be reduced to the new diameter of the printing rollers if the machine is to operate satisfactorily. It is therefore apparent that there must be a gum water roller for each set of printing rollers of a given size, or the gum water rollers must be cut down each time a new size of printing roller is used.

According to my invention, I use a gum roller of any suitable diameter regardless of the diameter of the printing rollers and support it in such a way that it rotates freely and independently of the rotation of the positively driven cylinder and printing rollers. In other words, the gum roller is not geared to or driven with the cylinder or the printing rollers.

One embodiment of my invention is illustrated in the drawings accompanying the present specification and in which

Figure 1 is a side elevation represented diagrammatically and with overlying portions omitted.

Figure 2, a detail with a portion of a mandrel supporting bearing shown in vertical longitudinal section, and

Figure 3, a detail end view of a gum water roller and a portion of the supporting means therefor.

Referring to the drawings my invention is shown as applied to a textile printing machine having a cylinder 1, printing rollers 2 and means for driving said cylinders and printing rollers in synchronism including a main gear 3 mounted on shaft 4, which also carries the cylinder 1, and gears 5 mounted on mandrels 6 carrying the rollers 2. Main gear 3 is actuated by a pinion 7 mounted on a shaft 8 which may be driven from any suitable source of power, as an electric motor, not shown. Color pans and other devices commonly utilized with the printing rollers are not shown since they have no significance in connection with the present invention.

At a suitable portion of the framework 9 of the machine, I provide a movable bearing 10 adjustable toward and away from cylinder 1, in a manner common to machines of this character. A gum water roller 11 on shaft 12 is freely rotatable with respect to said bearing, being preferably supported by

suitable anti-friction means such as roller bearings, ball bearings 13 or the like. A second gum water roller 14 is indicated in Figure 1 between printing rollers 2, 2 and is mounted substantially the same as gum water roller 11. A web 15 of fabric to be printed is shown in position between cylinder 1 and the printing and gum water rollers above described.

From the foregoing description it will be apparent that, as web 15 is fed through the machine, the cylinder 1 and printing rollers 2 will operate positively while the gum water rollers 11 and 14 will be in free rolling contact with a portion of said web engaging the periphery of cylinder 1. Thus, for a given machine, a gum roller of any convenient and suitable diameter may be operated with sets of printing rollers of the same or any other diameter without interrupting the smooth and effective passage of web 15 through the machine. Thus, with no extra expenditure of time and labor it is possible to produce sharply defined printings on fabrics, a result heretofore difficult to attain without the most careful preparation and adjustment of the printing and gum water rollers. It will also be apparent that the improvement hereinabove described may readily be incorporated in existing machines at little expense and without materially altering the design thereof. Other advantages and benefits inherent in my invention will be apparent to those familiar

with textile printing machines and their mode of operation.

I claim as my invention:

1. In a textile printing machine, the combination of means for feeding and printing a web of fabric including a cylinder, a print roller and means for driving said cylinder and print roller, and a gum water roller mounted to rotate freely and having its peripheral surface positioned for rolling contact with a web of fabric engaging said cylinder.

2. In a textile printing machine, the combination of means for feeding and printing a web of fabric including a cylinder, a print roller and means for driving said cylinder and print roller, and a gum water roller mounted to rotate independently of said driving means and having its peripheral surface positioned for rolling contact with a web of fabric engaging said cylinder.

3. In a textile printing machine, the combination of means for feeding and printing a web of fabric including a cylinder, a print roller and means for driving said cylinder and print roller, and a gum water roller freely rotatable on anti-friction bearings and having its peripheral surface positioned for rolling contact with a web of fabric engaging said cylinder.

In testimony whereof, I have signed my name to this specification this 2nd day of March, 1927.

JOHN W. WOLSTENHOLME.
